CLAIM

The ornamental design for a microscope, as shown and described.

DESCRIPTION

FIG. 1 is a front perspective view of a microscope in accordance with the new design.

FIG. 2 is a rear perspective view thereof.

FIG. 3 is a front view thereof.

FIG. 4 is a rear view thereof.

FIG. 5 is left side view thereof.

FIG. 6 is a right side view thereof.

FIG. 7 is a top view thereof; and,

FIG. 8 is a bottom view thereof.

FIG. 9 is enlarged view of the area indicated by "FIG. 9" in FIG. 1.

FIG. 10 is enlarged view of the area indicated by "FIG. 10" in FIG. 1; and,

FIG. 11 is enlarged view of the area indicated by "FIG. 11" in FIG. 2.

The unevenly dashed lines in the drawings demarcate enlarged views and form no part of the claimed design. The evenly dashed broken lines shown in the drawings illustrate portions of the article and form no part of the claimed design.
